UNITED STATES PATENT OFFICE.

JULIAN B. JENSEN, OF ALAMEDA, CALIFORNIA.

DESIGN FOR A ROTARY-PUMP CASING.

58,188.

Specification for Design. Patented June 21, 1921.

Application filed February 24, 1920. Serial No. 361,000. Term of patent 7 years.

To all whom it may concern:

Be it known that I, JULIAN B. JENSEN, a citizen of the United States, and a resident of Alameda, county of Alameda, State of California, have invented a new, original, and ornamental Design for a Rotary-Pump Casing, of which the following is a specification, reference being had to the accompanying drawing, forming part thereof.

Figure 1 is a front elevation of the pump

casing. Fig. 2 is a rear elevation of the pump casing and Fig. 3 is a plan view thereof.

I claim:

The ornamental design for a rotary pump casing, substantially as shown.

JULIAN B. JENSEN.
